FIG. 3

UNITED STATES PATENT OFFICE

2,519,046

COIN CONTROL DEVICE

Charles J. Hull, Kenmore, N.Y., assignor to The
Rudolph Wurlitzer Company, Chicago, Ill., a
corporation

Application July 13, 1946, Serial No. 683,547

3 Claims. (Cl. 194—9)

1

This invention relates to a coin control device for rendering effective electromagnet circuits for coin operated mechanisms, and has to do particularly with the initiating of the several operations of such mechanism before the coin deposited is finally accepted.

In coin operated machines, it is customary for the coin deposited to initiate the several required operations by closing switches in the control circuit as it passes through the coin chute. While the usual method of closing a switch by passage of the coin provides a more or less momentary impulse, it is not always effective to do the work, since there is a lag in the response of the electromagnetic device to the closing of the switch through which it is energized.

It is the object of this invention to provide a delaying action in the momentary closing of the circuit to the controlling electromagnet or magnets by causing the coin to hold the circuit closed beyond the end of any possible lag in the response of the electromagnetic devices. The invention has the advantage of making certain that an electric connection will be so complete and prolonged that not only saturation of the electromagnets in the circuit is assured, but that other operations may be timed to fall within the interval of saturation or delaying action, should such condition be desirable. This is accomplished by providing a motor controlled coin retaining mechanism, such that the coin is retained in switch closing position during a predetermined period of time sufficient to accomplish the above purposes.

The full nature of the invention will be understood from the accompanying drawings and the following description and claims.

Fig. 1 is a perspective view illustrative of a coin box with the coin control device associated therewith.

Fig. 2 is a section taken on the line 2—2 of Fig. 1.

Fig. 3 is a schematic diagram of the motor control circuit.

For illustrating one application of the coin control device to a coin box, there is shown in schematic perspective a coin box of the character disclosed in Letters Patent No. 2,292,628, granted August 11, 1942, to Benjamin W. Fry, entitled "Coin Selector." The coin box includes a housing 10 embracing a coin entrance slot 11, such as will receive coins of different denominations, for example, five, ten and twenty-five cent pieces. As the coins pass through their respective chutes, they are weighed in by a scale indicated at 12 and otherwise gaged to separate slugs from the

2

coins, the slugs dropping into the receptacles indicated at 13, 14 to drop from the bottom thereof. The coins after such segregation are directed into their respective coin passages according to their denomination, as indicated at 15, 16 and 17. In passing downwardly therefrom for acceptance they are directed to position for closing their respective control switches.

As shown in Fig. 2, the passage 15 receives a five cent coin 18; the passage 16 is similarly adapted to receive a ten cent coin and the passage 17 to receive a twenty-five cent coin. Below the coin box and said passages a gang of switches 21, 22 and 23 are arranged to expand outwardly from the switch block 24 secured to the underside of the box. In alignment with the gang of switches there are a corresponding number of switch actuating levers 25, 26 and 27, all of which are fulcrumed to a hinge bar 28 secured to the underside of the coin box. Said switch levers are provided with an insulating head on one end of each of them arranged to engage the switches 21, 22 and 23, respectively. Said switches are in the form of normally open spaced spring contacts, the lowermost of which is engageable by one of said heads for movement into contacting relation with its associated spring arm to close a circuit therethrough. Said switch levers are provided on the other side of their fulcrum point with an extension terminating in a laterally bent finger 29 arranged to extend transversely of one of the coin slots 15, 16 and 17 for engagement by a coin dropping therethrough.

The above described arrangement is such that upon the five cent coin 18 passing through the slot 15, it will engage finger 29 on its switch lever 25, causing the head thereof to engage and close the switch 21. The switch 21, as hereinafter described, will close a circuit through the control mechanism to be actuated by the five cent piece. Similarly, the ten cent piece will actuate its switch lever 26 to close the switch 22 and the twenty-five cent piece will actuate its lever 27 to close the switch 23. In order that said switches may be held in closed position for a predetermined interval to saturate the control circuits, the following described coin control or time delay device is provided.

Mounted upon or otherwise associated with the coin box 10 there is an electric timing motor 30 which is supported upon a gear housing 31 containing the usual train of speed reduction gears through which the motor driven shaft 32 is driven. Said shaft has its bearing in the housing 31 and

externally thereof has keyed thereto the control cam 33. Also mounted on said shaft 32 there is provided a motor limit switch 34 and a relay limit switch 35. Fulcrumed upon said housing 31 at 36 there is a coin retaining lever provided at one end thereof with a follower 37 engageable with the cam 33. At the other end of said lever which extends downwardly and under the coin box 10 there is provided a coin arresting arm having a claw with a plurality of laterally and upwardly extending tynes 38. Said tynes are arranged to extend under the coin slots to receive the respective coins therebetween. The coin receiving spaces between the tynes are of such depth relative to the diameter of the respective coins that although said coins will be received therebetween and permitted to drop sufficiently far to engage and rest upon their respective fingers 29, they will not be permitted to entirely pass therethrough. Thus, when the claw is in its normal forward position, the coin will be restrained thereby to rest upon its finger 29 and by its weight cause its switch lever to hold its switch contacts in closed position.

The follower 37 is biased against the cam 33 by a tension spring 39 having one end connected to the housing 31 and the other end to the downwardly extending claw arm. Thus, upon rotation of the cam by the motor, said cam through the action of the spring will retract the claw after a predetermined interval of time, to permit the restrained coin to drop free of its switch closing finger 29, whereupon the actuated switch will spring to open position. After this lapse of time, the circuit controlled by said switch will have completed its function.

The motor control circuit is diagrammatically illustrated in Fig. 3 as applied to a multicoin selective phonograph. Closing of any one of the coin switches 21, 22, or 23, completes a circuit from ground through one of the contact arms, a, b, or c, and arm d, all rotatably mounted on a common mounting plate 40, then through the coin relay coil 41 to a 24 volt relay supply 42. This energizes the relay coil 41 which is then maintained in an operating condition by the interlock contacts 43 which are in series with the relay limit switch 35. The closing of the relay 41 also closes the circuit from the source S through the motor 30 and a pair of contacts 45 which are in parallel with the motor limit switch 34. Closing of the isolation registration contacts 47 by relay 41 controls the phonograph accumulator not here involved.

As the motor 30 rotates, the contact arms, a, b, c, and d, relay limit switch 35 and motor limit switch 34 rotate with it on shaft 32. As the contact arms rotate, the short arm d moves from contact segment No. 1 and contacts segment No. 2. At the same time the long contact arms, a, b, and c, move into engagement with the small contacts 6, 7, and 8, wired in parallel with contact segments 3, 4, and 5. This provides a pulsing circuit to the accumulator coil 49 which evaluates the coin to register the number of record plays corresponding to the closed coin switch 21, 22, or 23. After the contact arms have passed the last coin registering contact in the circuit, the coin retaining tynes 38 release the coin, opening the coin switch and shortly thereafter the relay limit switch 35 opens and releases the coin relay 41. Following this action the motor limit switch 34 opens and stops the motor 30 which has completed one full cycle.

The coin arresting arm claw and likewise the

switches 21, 22 and 23, according to the coin or coins deposited, will be respectively held in retaining and closed positions, as shown in Fig. 1, for such interval as is required for the follower 37 to move over the outer dwell of the cam 33. The follower will then drop to the inner dwell of the cam, causing release of the coins and retaining the claw in its retracted position for a time interval, whereupon the follower will ride to the outer dwell which will reset the claw to its coin retaining position.

Whereas the above described structure is illustrative of one embodiment of the invention, it is believed obvious that various devices may be employed in place of the motor driven cam for moving the restraining claw to coin releasing position after a predetermined interval of time; similarly electromagnetic means may be employed, all to the end that upon a circuit being initiated by the coin, the coin will be restrained in circuit closing position for such time interval as to permit of electrical saturation of the circuit and the magnetically actuated devices thereof.

The invention claimed is:

1. In a motor controlled coin arresting mechanism having a plurality of adjacent coin passages each adapted to receive a coin of a different denomination, a timing motor and an electric circuit therefor, the combination therewith of a coin arresting arm fulcrumed on said mechanism intermediate its ends, one end thereof terminating in a plurality of laterally extending tynes below said passages for receiving the respective coins therebetween, a cam driven by said motor engageable with the opposite end of said arm, a series of control switches in said circuit biased to normally open position, and a switch control lever associated with each switch normally biased to a position under one of the spaces between said tynes for receiving and supporting a coin between said tynes, the weight of which is adapted to close its associated switch, said cam being operable to swing said arm from coin arresting position after a predetermined time interval determined by said motor to permit said coin to drop from its supporting lever and the return of its associated switch to normal open position.

2. In a motor controlled coin arresting mechanism having a plurality of adjacent coin passages each adapted to receive a coin of a different denomination, a timing motor and an electric circuit therefor, the combination therewith of a coin arresting arm fulcrumed on said mechanism intermediate its ends, one end thereof terminating in a claw having a plurality of spaced tynes extending below said passages between which said coins are received, a cam driven by said motor engageable with a cam follower on the opposite end of said arm, a series of spring leaf control switches in said circuit normally sprung to open position, and a switch control lever fulcrumed on said mechanism intermediate its ends associated with each switch with one end thereof normally biased to a position under one of the spaces between said tynes for receiving and supporting a coin in association with the claw of the coin arresting arm, the weight of the coin on said lever forcing the opposite end thereof against its associated switch to move one of its spring leaves to circuit closing position and thereby cause said motor to be driven, said cam being operable by said motor to swing said arm from coin arresting position after

a predetermined time interval to permit said coin to drop from its supporting lever and the return of its associated switch to its normal open position.

3. In a motor controlled coin arresting mechanism having a plurality of adjacent coin passages each adapted to receive a coin of a different denomination, a timing motor and an electric circuit therefor, the combination therewith of a coin arresting arm fulcrumed on said mechanism intermediate its ends, one end thereof terminating in a laterally extending claw having a plurality of spaced tynes positioned below said passages for receiving the respective coins therebetween, a normally open spring leaf switch in said circuit associated with each space between said tynes, the depth of the space between said switch and said tynes in relation to the diameter of the coin received therebetween being adapted to arrest the passage of the coin therethrough and hold it in switch closing position, a cam driven by said motor engageable with the opposite end of said arm for retaining said tynes in coin arresting position with respect to said switches and permitting said tynes to be withdrawn from coin supporting position for coin release therefrom

after a predetermined time interval determined by said motor, the release of said coin by the withdrawal of said tynes relieving the coin pressure on said switch to permit it to open the circuit to said motor.
